UNITED STATES PATENT OFFICE.

ALEXANDER MCLEAN NICOLSON, OF TARRYTOWN, NEW YORK, ASSIGNOR TO WESTERN ELECTRIC COMPANY, OF NEW YORK, N. Y., A CORPORATION OF ILLINOIS.

AUDION.

1,130,008.

Specification of Letters Patent.

Patented Mar. 2, 1915.

Application filed June 6, 1914. Serial No. 843,503.

To all whom it may concern:

Be it known that I, ALEXANDER MCLEAN NICOLSON, a subject of the King of Great Britain, residing at Tarrytown, in the 5 county of Westchester and State of New York, have invented certain new and useful Improvements in Audions, of which the following is a full, clear, concise, and exact description.

10 This invention relates to thermionic repeaters such as audions and of the high-current output type, and its object is to increase the efficiency of such repeaters.

One of the factors determining the efficiency of audions is the strength of the electric field between the input electrode and the filament. It has been discovered that by providing an input electrode having a large surface, and by placing the filament in close 15 relation to such surface, an extremely strong electric field is produced, resulting in correspondingly increased efficiency. By winding the filament about the input electrode, said input electrode offers the minimum obstruction between the filament and the plate, and this further increases the efficiency of 20 this type of audion.

The present invention, therefore, contemplates an audion provided with an input 25 electrode having a large surface. Such input electrode, for example, may be in the form of a plate, and the filament may be wound about said plate and maintained out of electrical contact therewith by a suitable 30 dielectric.

The invention may be more readily understood by reference to the drawing, showing in perspective an audion embodying the invention.

40 Referring to the drawing, the input electrode is shown as consisting of a plate 1. The filament 2 is wound about such plate and is maintained in proper position thereon by notches 3 in the edge of the plate, which 45 notches receive the filament. In this structure the filament lies against both surfaces of the plate 1, and the plate 1 may be covered with a dielectric coating at the points of contact of the filament therewith. The 50 output electrode is shown in two parallel plates 4, 4, lying upon opposite sides of the

plate 1 and parallel therewith. The plates 4, 4 are brought in close relation with the plate 1, such position of the parts having been found to be conducive to a high-current 55 output in the audion.

In the structure above described it will be noted that the input electrode and the output electrode each has a large surface and that said surfaces are in parallel relation to 60 each other. This, it has been discovered, is conducive to an efficient high-current output. As usual, the filament, the input electrode and the output electrode are inclosed in an evacuated bulb 5, the leading-in wires 65 to said elements being sealed in the bulb.

What is claimed is:

1. An audion provided with an input electrode having a large surface, and a filament wound about said input electrode. 70

2. An audion provided with an input electrode and an output electrode, each having a large surface, said surfaces being parallel to each other, and a filament extending about said input electrode. 75

3. An audion having its input electrode in the form of a plate and having its filament wound about said input electrode.

4. An audion having an input electrode in the form of a plate, a filament wound about 80 said plate, and an output electrode in the form of a pair of plates parallel to said input electrode plate and upon opposite sides thereof.

5. A thermionic repeater having its input 85 and output electrodes in the form of parallel plates, and having a heated cathode interposed between said plates and in close proximity to said input plate.

6. A thermionic repeater having its input 90 electrode in the form of a plate, its output electrode in the form of two plates parallel to said input plate upon opposite sides thereof, and a heated cathode on each side of said input plate and in close proximity 95 thereto.

In witness whereof, I hereunto subscribe my name this 3 day of June, A. D. 1914.

ALEXANDER MCLEAN NICOLSON.
